LIMIT SWITCH

Gustaf A. Halfvarson, Verona, Pa., assignor to
Westinghouse Electric & Manufacturing Com-
pany, a corporation of Pennsylvania

Application May 27, 1929. Serial No. 366,285

7 Claims. (Cl. 200—71)

My invention relates to switches of the tumbler type wherein the switch arm is actuated to an over-center position in response to the movement of the actuating member.

5 One object of my invention is to provide a switch of the above mentioned type that shall have an actuating member that may be operated by a cam passing thereacross.

A further object of my invention is to provide 10 a switch of the above mentioned type with restraining means that shall prevent the movement of the switch arm from either of its positions after the spring toggle has passed beyond its over-center position and until the actuating 15 means has reached a predetermined position.

Difficulty has been experienced heretofore in cam-actuated switches because of the straining of the various members when the cam that passes over the actuating member is bent or is out of 20 adjustment and thereby forces the actuating member beyond the switch-closed position.

In practicing my invention, I provide a spring-toggle connection between a rocker member and an actuating member that is so associated there- 25 with that the rocker member may pass beyond the switch-actuated position to a position below the supporting structure of the rocker member. In such construction, when the cam is out of ad- 30 justment, the actuating member may be moved beyond the switch position and, as this movement is not limited until the member has passed below 35 its supporting structure, the supporting structure itself must thereby take the strain of the cam, provided it is bent from its normal position a sufficient amount.

It is, therefore, a further object of my invention to provide an actuating member for a switch of the above-mentioned type that may be moved out of the path of an actuating cam beyond the 40 switch position and below the support for the said actuating member.

It is a still further object of my invention to provide a contact finger for a switch mechanism that shall be simple in construction and char- 45 acterized by the ease with which it may be removed and renewed.

With these principles and objects in mind, my invention will best be understood by referring to the accompanying specification, taken in con- 50 junction with the drawing, wherein

Fig. 1 is a view, in elevation, of a switch mech-
anism embodying my invention;

Fig. 2 is a view in section, of the structure shown in Fig. 1, taken along the line II—II;

55 Fig. 3 is a sectional view of the structure shown in Fig. 1, taken along the line III—III;

Fig. 4 is a view in section, of the structure of Fig. 1, taken along the line IV—IV;

Fig. 5 is a view in elevation, of a contact finger 60 shown in Figs. 1 and 2, and

Fig. 6 is an end view of the contact finger shown in Fig. 5.

My invention comprises, in general, an insulating base 1 and uprights 2 and 3 fastened thereto by means of bolts 4 and 5. The base 1 is also the means of supporting contact members 6 through which the circuit is completed by the bridging member 7.

The uprights 2 and 3 support a shaft 8 at their upper ends. An actuating member 9 which is journaled in the uprights 2 and 3 between the base and the shaft 8, comprises a crank portion 10, and the axial portion 19 supporting an insulating spool 11 upon which the bridging member 7 is clamped and by which the member 7 is insulated from the actuating member and from the uprights 2 and 3.

Referring to Fig. 4, the end of the actuating member 9 adjacent to the upright 2, which end constitutes a part of the crank thereof, is provided with a curved surface having an indented portion 12 that forms shoulders 13 and 14. Latches 15 and 16 are pivotally supported on the inner side of the upright 2 by pins 17 and 18. A spring 21 connects the latches 15 and 16 to bias them toward each other. As the actuating member 9 is rotatively moved, the latches slide over the surface thereof until one of them engages one of the shoulders 13 and 14 to latch the member in that position.

A rocker 22 is mounted on the shaft 8 and is positioned thereon in alignment with the crank of the actuating member 9 by a spacing sleeve 23. A pair of arms 24 and 25 are provided on the rocker 22 to extend above the shaft 8. A roller 26 is pivotally supported on each of the arms 24 and 25 by pins 27.

The rocker 22 has extensions 28 directly below the supporting shaft 8 that are provided with openings 31 in the bottom of which rest projections 32 from washer 29 which slides on a spring-toggle link 33. A washer 35 on the lower end of the link 33 is disposed in an opening 30 in the lower or crank pin section of the crank portion 10. Projections 34 on the washer 35 engage in a groove 36 formed in the lower side of said crank pin section. By so connecting the spring-toggle link 33 to the actuating member and the rocker, it may be removed therefrom, as a unit, by merely twisting it out of the groove 36 and the openings 31.

The side of the extension 28 of the rocker 22 adjacent to the upright 2 is provided with a projection 37 above the opening 31 thereof to act as a cam to engage one of the latches 15 and 16, 115 as the rocker is moved from either of its positions.

Extensions 38 are provided at the sides of the extension 28 which are of such length and shape that they engage the crank of the actuating 120

member 9 just after the projection 37 has released the latch 15 or the latch 16. The construction provides a positive engagement between the rocker 22 and the actuating member 9 to initially move it from either of its positions. Such construction is desirable to assure the initial movement of the contact members, which may resist the actuating force exerted by the toggle link 33, because of oxidation of the metal 10 of the said contact members, or because of resistance from any other cause.

Stops 39 are provided on the inner side of the upright 2 for engaging the crank 10 of the actuating member 9 to thereby position the bridging member 7 to either its "on" or its "off" position.

Each contact member 6, comprises an angular supporting member 40 that is fastened to the base by a bolt 41 and is connected to an electric circuit through a bolt 42. A slot 43 in the top and slots 44 in the sides of the support 40 are provided to support a finger 45 thereon. The finger 45 comprises a conducting member, bent to the shape shown in Figs. 5 and 6, and has an aperture therein through which a rivet 46 extends. The rivet 46 has an enlarged head on each of its ends that retains it on the finger 45, washers 47 and 48 and a spring 49 being mounted on the rivet.

The central portion of the bottom end 51 of the finger 45 is cut away to form two projections 52. The projections 52 engage the slots 44 of the supporting structure 40 after the rivet 46 has been inserted in the slot 43 thereof. Such construction permits outward movement of the fingers 45 caused by movement of the bridging member 7 between them. If it is desired to release a finger 45 from the supporting member 40 it is only necessary to move it inwardly beyond its normal position. This movement disengages the projections 52 from the slots 44 and permits the rivet 46 to be moved upwardly out of the slot 43. Thus, a small inward and upward movement removes the contact finger 45 from its supporting member 40.

It is to be understood that, while only a single set of contact members is shown in the drawing, any number may be employed by lengthening the supporting shaft 8, the base 2 and the axis 19 of the actuating member 9 and by providing additional contact fingers 6, bridging members 7 and insulating spools 11. When the words "on" and "off" have been employed, it is to be understood that, if a plurality of contacts 55 are employed, some may be moved to the one or to the other position at each operation or all may be either completing a circuit or opening one.

The operation of my switch will now be described.

Assuming the switch to be in the closed position shown in Fig. 2 and an actuating cam 53 to be moving across the rollers 26, it will be noted that the left-hand roller will be first engaged by the cam and moved downwardly to rotate the rocker 22 in counterclockwise direction. As pointed out above, the possibility of such movement beyond switch-closed position is one of the objects of the invention and is obtained through the association of the structures hereinbefore described.

Continued movement of the cam 53 causes the rocker 22 to move in a clockwise direction by engagement of the cam 53 with the right-hand roller 26. The clockwise movement moves the ex-

tension 28 in a clockwise direction, thereby stressing the spring of the toggle link 33 and causing it to be moved to its over-center position.

In such position, the actuating member 9 should be moved to operate the bridging member 7 but, as pointed out above, this is prevented by the engagement of the latch 15 with shoulder 13 of the actuating member 9. Continued movement of the rocker 22 moves the projection 37 thereon into engagement with the latch 15 to move it out of engagement with the projection 13 after the spring toggle 33 has been compressed a predetermined amount.

This release permits the actuating member 9 to move the bridging member 7 out of engagement with the fingers 6. At the time that the latch 15 is disengaged from the projection 13, the extension 38 has moved or is about to move into engagement with the crank of the actuating member 9 to apply a force thereto to initially move the bridging member 7 from engagement with the fingers 45.

In the closing operation, the same cycle of stressing the toggle, releasing the latch and positively moving the actuating arm 9, is passed through, and the actuating arm 9 is then latched in the closed position, as shown.

It will thus be seen that I have provided a tumbler-type switch that is latched in either of its positions and is thereby moved from or to either of its positions only after the biasing means to move it has been stressed a predetermined amount. The latches employed to retain the mechanism against the bias has an additional utility of retaining the contact members in their desired positions until the latch has been released, through the movement of the rocker employed to actuate the switch.

My invention is further novel in so associating the rocker with the actuating arm that the former may be moved to either side of its normal position out of the path of the actuating cam and below its supporting structure. My contact structure is also novel in that a contact finger, which may become damaged from wear, is very simple in construction and may be removed by simply pushing it inwardly and upwardly.

While I have shown but a single embodiment of my invention, it is to be understood that additions, subtractions, omissions and substitutions may be made therein without departing from the spirit and scope of the invention. Therefore, I desire that the appended claims shall be limited only as may be necessitated by the prior art.

I claim as my invention:

1. A switch structure including a switch member, means for latching said member in either of two positions, an actuating member for said switch member, a link carrying a compression spring connecting said switch member with said actuating member, said spring biasing said switch member to one position until the actuating member has passed the center of its path of travel, and then biasing said switch member to the second position, and means for releasing said latch after the spring has biased the switch member to said second position.

2. A switch structure including a switch member, means for latching said member in either of two positions, an actuating member for said switch member, a link carrying a compression spring connecting said switch member with said actuating member, said spring biasing said switch member to one position until the actuating member has passed the center of its path of travel

travel, and then biasing said switch member to the second position, and means for releasing said latch after the spring has biased the switch member to said second position, said actuating member being movable beyond the positions to which it must move to change the position of the switch member.

3. A cam operated switch structure including a pivoted switch-actuating member, a rocker member pivoted about an axis spaced from the axis of the actuating member, the rocker member having a pair of arms adapted to be actuated by a cam, one of said arms being arranged to be engaged by the cam when the rocker member is in the first position to move the rocker member to the second position and the other arm being arranged to be engaged by the cam when the rocker member is in the second position to move the rocker member to the first position, and an over-center spring connection between the rocker and the actuating member exerting a bias on the latter in a direction toward the axis thereof, said spring connection being movable past the axis of the actuating member by movement of the rocker from a first position to a second position to move the actuating member from one position to another, said spring connection biasing the rocker to the first position when the actuating member is in said one position and to the second position when the actuating member is in said other position, and said rocker member being movable beyond said first and second positions against the bias of said spring connection to avoid damage to the switch structure in case of misalignment thereof with respect to the path of the cam.

4. In a cam operated switch-actuating structure, the combination of a switch-actuating member movable to first and second positions, a pivoted rocker member movable to first and second positions thereof for moving the actuating member to first and second positions, respectively, the rocker member having a pair of arms adapted to be actuated by a cam, one of said arms being arranged to be engaged by the cam when the rocker member is in the first position to move the rocker member to the second position and the other arm being arranged to be engaged by the cam when the rocker member is in the second position to move the rocker member to the first position, and spring means connecting the rocker member and the actuating member exerting a bias on the latter in a direction toward the axis thereof whereby the rocker actuates the actuating member, said rocker member being movable beyond the first and second positions thereof to avoid damage to the switch actuating structure in case of misalignment thereof with respect to the path of the cam, and said spring means biasing the rocker member to the first position thereof when the actuating member is in first position and to the second position thereof when the actuating member is in the second position.

5. A switch structure including a pivoted switch-operating member, means for latching said switch-operating member in either one of two positions, an actuating member pivoted about an axis spaced from the axis of the switch-operating member, an over-center spring connection be-

tween the switch-operating member and the actuating member, said spring connection having only a single line of action which is moved across the axis of the switch-operating member by movement of the actuating member, so that the spring connection biases the switch-operating member to its previously assumed position during the initial movement of the actuating member and to its new position after crossing the axis of the switch-operating member, means for releasing the latching means after the spring connection biases the switch-operating member to its new position, and means carried by the actuating member for moving the switch-operating member immediately after said latching means is released.

6. A switch-operating structure including a pivoted switch-operating member movable to closed-circuit and open-circuit positions, an actuating member for moving the switch-operating member, an over-center spring connection between the switch-operating member and the actuating member exerting a bias on the former in a direction toward the axis on which the switch-operating member is pivoted, said parts being so arranged that the line or direction of said bias is moved from one side of said axis to the other by movement of the actuating member and so that the spring connection biases the switch-operating member to its previously assumed position during the initial movement of the actuating member and to its new position after the line of bias has crossed the axis of the switch-operating member, a latch for holding the switch-operating member in one position, means for releasing said latch after the spring connection biases the switch-operating member to the other position, and means carried by said actuating member for moving said switch-operating member by positive engagement just after said latch is released.

7. A switch structure including a switch member movable to open and close the circuit, a pivoted switch-operating member movable to closed-circuit and to open-circuit position, an actuating member for moving said switch-operating member, an over-center spring connection between the switch-operating member and the actuating member, said spring connection exerting a bias on said switch-operating member in a direction toward the axis on which said switch-operating member is pivoted, said parts being so arranged that the line or direction of said bias is moved from one side of said axis to the other by movement of the actuating member and so that the spring connection biases the switch-operating member to its previously assumed position during the initial movement of the actuating member and to its new position after the line of bias has crossed the axis of the switch-operating member, a latch for holding the switch member in one position, means for releasing said latch after the spring connection has moved to bias the switch-operating member to the other position, and means operable by said actuating member for positively moving said switch member just after said latch is released.

GUSTAF A. HALFVARSON.
